UNITED STATES PATENT OFFICE.

HERBERT S. EADES, OF PHILADELPHIA, PENNSYLVANIA.

FEEDING MECHANISM.

Application filed May 1, 1923. Serial No. 635,905.

To all whom it may concern:

Be it known that I, HERBERT S. EADES, a citizen of the United States, and resident of Philadelphia, in the county of Philadelphia and State of Pennsylvania, have invented certain new and useful Improvements in Feeding Mechanisms, of which the following is a specification.

This invention relates to methods of and means for feeding granular material from a storage container to a point of use, and has for one of its objects the feeding of said material without the use of pushing screws, plungers, scrapers or any of the other usual mechanisms that involve a shearing or pushing action on the material being handled.

Another object is to provide a measured flow of material the volume of which may be varied as desired by the operator without the use of valves or other mechanical means.

A still further object is to provide a method consisting of the novel steps hereinafter set forth, and a feeding means composed of the novel construction and combination of parts hereinafter described and illustrated in the accompanying drawings.

In the drawings—

Figure 1 is a side elevation, partly in section, of a feeding device constructed in accordance with my invention.

Figure 2 is an end elevation of the apparatus of Figure 1.

Figure 3 is a longitudinal sectional elevation of a modified form of feeding device embodying my invention.

Figure 4 is an end elevation thereof.

Figure 5 is a longitudinal elevation of another modified feeding device embodying my invention.

Figure 6 is a sectional elevation of a still further modified feeding device for feeding granular material to an electric furnace or the like, the top wall of the furnace also being shown in section.

Figure 7 is an elevation of a portion of the feeding device of Figure 6, taken on the line VII—VII of Figure 6.

Referring more particularly to the drawings, in Figures 1 and 2 I have shown the simplest form of my invention, which consists of a storage bin or container 2 having an outlet orifice 3 communicating

through a nipple 4 with a rotary conveying tube 5. The tube 5 is twisted or bent to form a left-handed worm or spiral and has its rear end mounted for rotation on the nipple 4 while its forward end is supported by a bearing member 6 and terminates in a nozzle or delivery mouth 7 adapted to deliver the material into a hopper 8.

The tube 5 is positioned so that the axis of its delivery end is on a line with the axis of the outlet orifice 3, and any movement of the material through the tube must be caused by rotation of the tube.

A worm wheel 9 is secured to the rear end of the tube 5 and meshes with a worm 10 which may be driven by a motor or any other source of power, and thus rotate the tube 5 in a counterclockwise direction.

Each change of angularity of the tube 5 forms a separate containing chamber or recess. That is, the part nearest the bin 2 forms a receiving chamber or recess 11 into which the material will flow by gravity, the part extending upwardly and forwardly therefrom forming a second containing chamber or recess 12 into which the material will flow when the tube is rotated, and so on throughout the tube.

It will be readily seen that a continuous stream of material will travel through and be discharged from the tube 5 as said tube is rotated, and that by varying the speed of rotation of the tube, the quantity of material being fed through the tube may be varied.

The apparatus of Figures 3 and 4 is substantially the same as that of Figures 1 and 2, with the exception of the tube 5, which is of irregular shape instead of being spiral. The tube 5 of this apparatus is provided with a plurality of chambers or recesses 15 disposed on opposite sides of the axis of rotation and offset longitudinally relative to each other. Each of the chambers or recesses 15 is provided with a vertical front wall 16 and a rearwardly inclined rear wall 17 adapted to extend beyond the front wall of the chamber or recess on the opposite side of the axis of rotation so as to form communicating passages between the chambers or recesses 15 on the opposite sides of the axis of rotation, and provide for a step by step movement of the material with-

100

in the tube. The material will flow by gravity into the first chamber or recess 15 and as the tube is rotated the material will fall laterally onto the inclined wall 17 of 5 the chamber or recess on the opposite side of the tube and opposite the first chamber, which wall will move the material forwardly so that on the continual rotation of the tube it will move or fall laterally onto the inclined 10 rear wall 17 of the chamber or recess on the opposite side of the axis of rotation and forward of the first chamber. This combined lateral and forward movement of the 15 material will continue through the several chambers or recesses 15 until it is finally discharged through the outlet port or nozzle 7 into the hopper 8.

In Figure 5 I have shown a conveying tube or barrel 5^a employing the same general principles as the conveying tubes of 20 Figures 1 to 4, but of somewhat different construction. The conveying tube 5^a of Figure 5 comprises a cylindrical barrel-like body portion provided with a series of helical flights or screw-blades 20 formed integral therewith. In this construction the material to be fed will flow around the interior of the body of the tube as the tube is rotated and due to the helical or spiral arrangements of the flights 20 will be fed forwardly toward the forward end of the barrel or tube from which it will be discharged into the hopper 8.

In Figures 6 and 7 I have shown a modified construction of apparatus especially adapted for feeding granular material into an electric furnace or the like. In this construction the conveying tube 5^b is adapted to 35 discharge the material conveyed thereby into 40 a funnel 8^a mounted in an opening in the top wall 23 of the furnace.

The tube 5^b is formed from a single casting and comprises a tubular inlet opening 24 and a tubular outlet opening 25, said portions being connected by tubular by-pass 45 portions 26 and 27 which are disposed on opposite sides of the parts 24 and 25 and form opposite chambers or recesses into which the material passes during rotation of 50 the tube. The tube is disposed on an angle of approximately 45 degrees so that the material will move forwardly through the tube when it is rotated to cause a lateral shifting of the material.

55 It will be readily seen that the material will flow by gravity into the recess or by-pass portion 26 and that the portion 27 will be filled as the tube is rotated. Also that this portion will be filled before any great 60 amount of the material from the portion 26 moves laterally due to the rotation of the tube. After the portion 27 has become filled or nearly filled with the material from the bin 2 the material from the portion 26 will 65 move laterally and the major portion will

be compelled to flow out of the discharge or outlet portion 25 and into the hopper 8^a. Continued rotation will cause a steady stream to flow from the tube 5^b.

In each of the above arrangements of apparatus the material to be conveyed flows through the outlet or discharge orifice of the storage bin by gravity and is collected in a rotary conveyer having a recess or chamber adapted to accumulate a predetermined amount of material and restrict further gravity feed through the orifice, and upon rotation of the rotary conveyer the material is passed progressively through a series of recesses or chambers so disposed as to cause a lateral and longitudinal movement of the material, thus causing it to travel through the conveyer tube and be discharged, the quantity of which may be varied by varying the speed of rotation of the tube. It will also be readily understood that the flow of material may be stopped by stopping the rotation of the tube, and that no valves are necessary.

90 It will be noted that each of the combinations of apparatus shown above includes a conveying tube or barrel having recesses or chambers on opposite sides of the axis of rotation through which the material being fed is compelled to pass, and that all of the constructions have a tortuous flow path which intersects the axis of rotation and, therefore, prevents a continuous flow through the tube unless the tube is rotated to cause the material to move from one chamber or recess to the other with a combined lateral and longitudinal movement.

95 While I have shown and described several different forms and embodiments of my invention, it will be understood that I do not 100 wish to be limited thereto, since various further modifications may be made without departing from the scope of my invention as defined in the appended claims.

105 I claim:

110 1. In apparatus for feeding material from a source of supply to a point of use, a container adapted to contain a quantity of the material to be fed, said container having a discharge orifice below the level of the material therein for the gravity discharge of the material, a rotary conveyer co-operating with said orifice and adapted to receive the material as it flows through said orifice, said conveyer having recesses longitudinally offset relative to each other, and means for 115 rotating said conveyer to cause the material to pass progressively from one recess to the next, said conveyer having an outlet opening in axial alignment with said orifice, 120

125 2. In apparatus for feeding granular material from a source of supply to a point of use, a container adapted to contain a quantity of the material to be fed, said container having a discharge orifice below the 130

level of the material therein for the gravity discharge of the material, a rotary conveyer co-operating with said orifice and adapted to receive the material as it flows through said orifice, said conveyer having recesses laterally offset on opposite sides of the axis of said orifice, means for rotating said con-

veyer to cause the material to pass progressively from one recess to the other, and said conveyer being provided with an outlet ¹⁰ opening in axial alinement with said orifice.

In testimony whereof I have hereunto signed my name.

HERBERT S. EADES.
